UNITED STATES PATENT OFFICE.

EDWARD E. LAWRENCE, OF CAMBRIDGE, MASSACHUSETTS, ASSIGNOR TO LOOSE WILES BISCUIT COMPANY, OF KANSAS CITY, MISSOURI, A CORPORATION OF MISSOURI.

MECHANISM FOR FORMING FILLED WAFERS.

1,169,546.

Specification of Letters Patent.

Patented Jan. 25, 1916.

Application filed January 25, 1912. Serial No. 673,355.

To all whom it may concern:

Be it known that I, EDWARD E. LAWRENCE, a citizen of the United States, and a resident of Cambridge, in the county of 5 Middlesex and State of Massachusetts, have invented an improvement in Mechanism for Forming Filled Wafers, of which the following description, in connection with the accompanying drawings, is a specification. 10 like characters on the drawings representing like parts.

This invention relates to mechanism for and process of forming filled wafers.

In order that the principle of the invention may be readily understood, I have disclosed a single embodiment thereof in the accompanying drawings, wherein—

Figure 1 is a plan view of one form of mechanism embodying my invention and for carrying out my process; Fig. 2 is a front elevation thereof; Fig. 3 is a side elevation thereof; Fig. 4 is a plan view on an enlarged scale of a portion of the mechanism shown in Fig. 1 and representing also a portion of 20 the wafer sheets; Fig. 5 is a vertical longitudinal section of a portion of the apparatus; Fig. 6 is a transverse section taken through a portion of the apparatus; Fig. 7 is a plan view of the mold wherein the 25 wafer sheets may be formed, and showing the same open; Fig. 8 is a plan view of a portion of the complete wafer sheet before segregation; Fig. 9 is a transverse section taken therethrough; Fig. 10 is a plan view 30 of one sheet of another form of filled wafer; Fig. 11 is a plan view of the other sheet thereof; Fig. 12 is a transverse section taken through both sheets and the filling; Fig. 13 is a plan view of another form of apparatus 35 embodying my invention and for practising my method; Fig. 14 is a longitudinal section of such form of apparatus; Fig. 15 is a transverse section thereof taken through the 40 hopper; Fig. 16 is a detail of said form of apparatus; Fig. 17 is a diagrammatic view 45 representing the simultaneous severance of the filled wafer sheets into ultimate pieces; and Fig. 18 is a transverse section taken 50 through the filled wafer sheets and the simultaneously acting cutters.

Filled wafers and like articles of food have heretofore customarily been formed by preparing wafer sheets in suitable molds and applying the filling to one of them by a

palette knife, which is manually drawn 55 across the entire surface thereof when positioned upon a slab or other suitable support, after which the other wafer sheet is superimposed thereon. Not only is the filling necessarily applied to the entire surface of 60 the sheet, but a considerable proportion thereof is wasted because spread onto the adjacent surrounding portions of the slab or other support. Moreover it is impossible in this manner of application to apply the 65 filling evenly to the sheet, and without either a deficiency or an excess of material. After the covering wafer sheet has been superimposed upon the filling, the sheets are subdivided into individual pieces. Not only is 70 there very considerable loss of filling that is not confined to the wafer sheet, but is spread onto the support, but there is also the loss of that portion of the filling applied to those parts of the wafer sheet that are 75 between the ultimate or segregated wafers. Particularly is this true when the wafer sheets are molded into spaced concavities in the formation of artificial nuts or similar articles which are ultimately severed close 80 to the concavities with the consequent loss of the flat or connecting portion of the wafer sheets. When a sheet has been molded into spaced concavities for the formation of artificial nuts or the like, it is a matter 85 of exceeding difficulty to apply the filling thereto without crushing a considerable percentage of the concavities or breaking the connecting portions of the wafer sheet, thus ruining the entire sheet. Furthermore 90 there is a very substantial loss in the breaking of the wafer sheets not only in the manual application of the filling thereto, but also in the cutting of the sheets into strips and into ultimate individual pieces. 95

In accordance with my invention, I mold the sheets into suitable form, which may be made by forming spaced concavities therein, after which the sheet is applied to a supporting plate having openings or concavities 100 therein corresponding in shape and position to the concavities of the wafer sheet, if the latter be so molded. I then superimpose upon the wafer sheet a die or stencil plate having openings corresponding in position 105 and size to the segregated area to which only the filling is to be applied. Thereupon I apply the filling preferably by relatively

reciprocating the supporting mold plate, the wafer sheet and the stencil or die plate with respect to the hopper. After the filling has been applied, the stencil plate is removed, 5 and then preferably the filled wafer sheet is inverted upon another filled wafer sheet by bringing the filled areas thereof into coincidence. In order to prevent breaking of the filled wafer sheets in the separation 10 thereof into individual pieces, I preferably simultaneously sever the wafer sheets by a gang of knives into the ultimate pieces and then subject said completed pieces to a cooling action to harden the filling, and there- 15 by effect the binding of the wafer sheets together by the hardened filling.

It will be evident that the discarded portions of the wafer sheet between the concavities or other formations do not contain 20 filling and that therefore there is not only no loss of filling, but that the said severed portions of the wafer sheets may themselves be employed in other processes of manufacture, that is to say, in the formation of other 25 products.

Referring more particularly to the drawings and first to Figs. 1 to 6 inclusive, I have therein represented a suitable frame or supporting table or bed 1, upon which is mounted 30 a skeleton frame 2, most clearly indicated in Fig. 5, adapted to receive upon the shouldered face 3 thereof a suitable supporting mold plate 4 which, in accordance with one embodiment of my invention, is 35 provided with openings 5. The supporting mold plate is provided with openings when the wafer sheet is molded into spaced concavities, in order that the said concavities may enter said openings and the sheet be 40 supported by the connecting flat portions of the sheet resting flatwise against the plate 4 between the openings 5 therein. While the plate 4 may be continuous throughout, I preferably form the same in two sections 45 A, B, clearly indicated in Fig. 4, and mount them upon parallel rods 6, 6, which are supported upon the shouldered portion 3 of the frame 2, so as to permit the two sections A, B of the plate 4 to be swung upwardly 50 to bring the wafer sheets into contact, as indicated in dotted lines in Fig. 6. The wafer sheets, which are composed of any usual material and which is generally thin and fragile, are formed by applying the dough to a 55 mold, such as indicated at 7, 8 in Fig. 7, wherein I have represented two members of a mold provided with concavities 9 and entering projections 10 to mold the dough or wafer sheet 11 therebetween into the desired 60 shape. I have herein chosen to disclose as a preferred embodiment of the invention the molding of a wafer sheet with spaced concavities to form nut sections, customarily known when completed as almonds or philo- 65 penas. After the wafer sheets have been

molded, I then apply two wafer sheets 12, 13 to the mold supporting plates A, B, as indicated most clearly in Fig. 4, after which I superimpose upon the wafer sheets a die or stencil plate 14 provided with openings 14' 70 corresponding in size and position to the concavities of the wafer sheets. The said die or stencil plate 14 may be a continuous sheet overlying both wafer sheets 12, 13. This die or stencil plate may be of any suitable material, but is preferably of copper, and in certain embodiments of my invention, as, for example, that disclosed in Figs. 1 to 6 inclusive, is made as thin as possible, 75 so that the amount of filling applied to the concavities 15 of the wafer sheets may protrude beyond the level of the wafer sheets to a minimum extent, but nevertheless sufficiently to insure the binding together of the wafer sheets by the meeting protruding 80 surfaces of the filling when two wafer sheets are brought into coincidence. In other forms of my invention, however, and particularly those wherein the wafer sheet is not molded into well defined concavities, the 85 stencil plate is customarily thicker, so as to 90 secure the application of thicker layers of filling thereto.

As shown most clearly in Fig. 5, the die or stencil plate 14 is wrapped or otherwise 95 secured at its rear end 16 about a transverse bar or rod 17 supported upon the frame and provided at its ends with rods 18 supported upon the frame and adapted to be swung upwardly as indicated in Fig. 3, so as to lift 100 the die or stencil plate off the wafer sheets after the latter have had the filling applied thereto. In order to apply the filling to the wafer sheet or sheets, I preferably provide a hopper 19 indicated most clearly in Figs. 1 and 5, wherein it is shown as of box like form having an open bottom 20 with preferably inclined lower walls 21. When the mechanism is not in operation, the hopper is supported at the rear of the die or stencil 105 plate upon an imperforate plate 22, which is itself supported upon the portion 23 of the frame. Preferably I provide the lower face of the hopper with longitudinally extending wipers 24 of felt or other suitable 110 material to insure the proper application of the filling to the openings of the stencil plate 14. The hopper 19 is provided with a suitable shaft 25, whereon is fast one or it may be a plurality of rotatable stirrers or 115 mixer blades 26, which serve to enforce the discharge of the filling through the open bottom 20 during the relative reciprocation of the hopper and the wafer sheet or sheets.

In the form of the invention shown in 120 Figs. 1 to 6 inclusive, I have represented the hopper as movable to and fro over the die or stencil 14. While any suitable means 125 may be employed to effect this result, I have herein represented the framing as having 130

fast thereon a pair of horizontal racks 27 extending from front to rear, and with which mesh the pinions 28 fast upon the shaft 25. At one or both ends, the shaft 25 extends beyond the pinion or pinions 28, and is there provided with a crank handle 29 and intermediate said handle or handles and the adjacent pinion 28, I provide a horizontal way 30 suitably supported upon 5 coiled spring or other yielding supports 31 and along which the hopper 19 travels back and forth across the die or stencil plate 14, upon rotation of the shaft 25. It will be obvious that in the to and fro reciprocation of the hopper 19, the filling is discharged only through the openings 14' of the stencil plate and that the filling is discharged in such measured or predetermined quantities that the filling also extends from 10 the base of the concavities to the upper face of the die or stencil plate 14, so that it protrudes beyond the level of the mouth of the concavities to an extent dependent upon the thickness of the die or stencil plate. In this 15 manner, I secure a predetermined slight excess of filling material which when two wafer sheets are brought into coincidence compels the binding or sealing together of 20 the wafer sheets thereby.

25 In former processes, so far as I am aware, either the filling material was supplied in such deficiency that it did not extend to or beyond the level of the wafer sheet, and thus did not effect the sealing or binding 30 of wafer sheets together, or it was applied in such excess that there was a great loss of filling material between the concavities and also the improper union of the wafer sheets.

35 In former processes so far as I am aware it was customary merely to support the molded wafer sheet upon an open slab and to spread the filling thereon by a knife or blade. If during the molding or prior to 40 the application of the filling the wafer sheet were broken, it was substantially impossible to use the broken sheet not only for the reason that the sheet could not be positioned to receive the filling, but because the broken 45 sheet could not be so positioned that after the filling, another sheet having corresponding concavities could be superimposed thereon into coincidence. This resulted in the loss of all broken sheets. In the practice of 50 my invention, however, in accordance with which the wafer sheets are positioned upon the mold plate or plates and are afterward covered with a stencil plate, it is an easy 55 matter to use broken portions of wafer sheets by fitting them onto the mold plates A, B with their concavities resting in the openings 5 thereof, it being immaterial that flat portions of the wafer sheets overlie. It 60 is a usual custom, in the practice of my invention, for the workman to keep a supply 65 of broken sheets from which he may quickly select a piece to patch out a wafer sheet from which he has been compelled to break off a damaged portion. In this manner substantially all loss of broken wafer sheets is 70 eliminated, and further than this the broken pieces are always correctly positioned with respect to the sheet that is to be superimposed thereon, because all portions of both sheets are correctly positioned by reason of 75 the openings 5 in the supporting mold plate 4.

After the filling has been applied to the wafer sheets and the hopper 19 has been returned to its inoperative position, the die 80 or stencil plate 14 is swung into elevated position, as indicated in dotted lines at 32 in Fig. 5, and thereupon the two sections A, B of the mold plate are swung into elevated position, as indicated at 33, in Fig. 6, so as 85 to bring the wafer sections together with the segregated filling areas in coincidence.

In Figs. 8 and 9, I have represented in plan and cross section a portion of superimposed filled wafer sheets, wherein at 34 is 90 represented the upper wafer sheet and at 35 the lower wafer sheet, and at 36 the filling which serves to bind or seal the wafer sheets together. The connecting or flat portions 37 of the wafer sheets are devoid of filling, as 95 indicated, so that all loss of filling between the concavities is wholly eliminated. After the filled wafer sheets have been brought into register or coincidence as described, or in any other suitable manner, I remove the 100 filled and adhering wafer sheets to a suitable severing mechanism shown diagrammatically in Figs. 17 and 18 and having a gang of knives 38 which are operated simultaneously so as to cut the filled wafer sheets 39 105 simultaneously into individual or ultimate pieces and avoid that breakage of pieces of wafer sections that necessarily occurs when the filled sheets are first severed into strips and then afterward cut transversely into 110 ultimate pieces. In order to prevent the slipping of the two sections of each completed piece upon each other, I harden the filling by cooling the ultimate pieces or the 115 filled sheets. Preferably I cool the individual piece after severance in any suitable manner.

Instead of molding or embossing the wafer sheets as described, I may employ 120 wholly flat sheets to make, mark or form them in any suitable manner for the reception of the filling. In Fig. 10 I have represented one face of a wafer sheet 40 having ridges or other substantially rectangular markings 41 thereon, and in Fig. 11 a second sheet 41' having its face provided with small diagonally arranged pockets or shallow recesses 42. If desired, each sheet may 125 have one face formed as shown in Fig. 10 and the opposite face as shown in Fig. 11, 130

or they may be formed or marked in any other suitable manner. These sheets are superimposed one upon the other as indicated in Fig. 12 after the filling 43 has been applied thereto in the manner already indicated, and then the filled sheets are severed by a gang of simultaneously operating knives in the manner already described.

In applying filling to a sheet, such as shown in Fig. 10 or Fig. 11, in accordance with the former method of procedure, the filling has been applied necessarily not only within the boundaries of the rectangular markings or formations 41, and to the narrow longitudinal and cross areas 44, but also to the surrounding areas 45, and in fact to the surrounding portions of the slab or support, as already set forth. When the filled sheets are severed by the gang of knives, to which I have referred, there is customarily cut out by the knives strips or pieces of material corresponding to the areas 44, 45. In the old method of procedure, these discarded areas were coated with filling, which was therefore necessarily lost. In accordance with my present invention, however, the stencil or die plate is provided with openings corresponding in position and size to the areas bounded by the markings or formations 41, and hence the filling is applied only within said boundaries in segregated areas, and no filling is lost when the filled sheets are severed.

In Figs. 13, 14, 15 and 16 I have represented a modified form of apparatus for practising my invention. Therein the hopper 46 is stationarily mounted upon the frame, being secured by bolts and wing nuts 46' to angle brackets 46'' secured to the side members of the frame, as indicated in Figs. 13 and 15, and is provided if desired with a stirrer or blade such as shown in Fig. 1. The framing 47 is provided with suitable ways whereon to reciprocate the wafer supporting plate together with the wafer sheets and stencil plate. Herein for the purpose I have represented the framing as provided with opposite shoulders or ways 48 whereon are mounted suitable tracks 49 having ball bearings 50 directly supporting the side bars 51, which at their under faces may if desired have inset therein metallic strips 52 with which the ball bearings 50 directly engage. Any suitable number of ball bearings may be provided for the purpose, or any other suitable supporting and guiding device may be substituted therefor. To the side bars 51 connected by channel bar 51' and also at their ends, I secure a wafer sheet supporting plate 53 which may be perforated or otherwise formed to support embossed or similar wafer sheets as described with respect to the preceding form of my invention, but which is herein shown as solid to support a wafer sheet of the general character shown in Fig.

10 or Fig. 11 normally underlying the hopper 46 in an imperforate plate 53' also supported upon said side bars 51. To the side bars 51 or to the supporting plate 53, I secure by side strips 54 a push bar 55 by means of which the supporting plate 53 and the plate 53' may be slid back and forth beneath the hopper, so as to permit the discharge of the filling upon the upper face of the wafer sheet. I preferably provide the plate 53 with side strips 55' to engage rubber or other cushions 55'' upon the frame. Upon the upper face of the wafer sheet I position the die or stencil plate 56 preferably hinged by tapered screws 56' in the side bars 51 taking into the cross piece 56'' thereof. Preferably, in this form of my invention, the die or stencil plate 56 is of a single piece, and after the wafer sheet positioned upon the supporting plate 53 has had segregated filling areas applied thereto and after the stencil plate 56 has been swung into elevated position in the manner previously described, a second sheet is superimposed thereon. This can readily be effected, because the second sheet is of the same size and shape as the filled sheet, and as its markings or formations need not correspond to those of the filled sheet, there is no necessity to make it register absolutely therewith. The openings 57 of the die or stencil plate 56 correspond in size and position to the outlines 41 of the wafer sheet to be filled, so that the filling is applied only within the confines of such area. Therefore in the cutting of the filled sheets after superposition of one upon the other, there is no loss of filling between the blades. The thickness of the filling that is to be applied to a substantially flat or non-embossed wafer sheet is the thickness of the die or stencil plate 56, which therefore is generally thicker than that employed in connection with the form of my invention shown in Figs. 1 to 6 inclusive.

It will be evident from the foregoing description that the filling may be applied at much greater speed than heretofore, and in measured predetermined quantities, so that neither an excess or deficiency in amount results, and furthermore the wafer sheets are protected while the filling is being applied thereto. A further and more important saving, however, is effected, because of the application of the filling to segregated areas only, so that when the sheets are severed into the ultimate pieces, no filling whatever is lost. Furthermore, owing to the fact that it is possible to use broken pieces of wafer sheets, a very large saving is thereby effected.

It will, of course, be evident that certain steps of the herein disclosed process may be carried out by hand, as for example, the depositing of the filling material in spaced areas. The molding of the wafer sheets may be effected in any suitable manner, and the

preferably simultaneous severing of the filled sheets into ultimate pieces may be carried out in any desired manner. The supporting sheet 4, or its substitute, may if desired be formed in a single piece, and after the wafer sheet supported thereon has been filled, another wafer sheet, either filled or unfilled, may be superimposed thereon in any suitable manner. Whether or not both wafer sheets are individually supplied with filling will depend generally upon the shape and configuration of the wafer sheets. Where, as in that form of my invention disclosed in Figs. 1 to 6 inclusive, the filled wafers are of the form of nuts or similar articles, I preferably apply the filling to both sheets and then superimpose one sheet upon the other in any desired manner.

Having thus described one illustrative embodiment of my invention and the best manner of carrying the same into effect, I desire it to be understood that although specific terms are employed, they are used in a generic and descriptive sense and not for purposes of limitation, the scope of the invention being set forth in the following claims:

1. Mechanism for forming filled wafers comprising in combination, a wafer sheet supporting plate having sections relatively movable into a face to face relation, a die or stencil plate mounted to be superposed thereon, and means for supplying filling through said die or stencil plate to the wafer sheet upon the supporting plate.

2. Mechanism for forming filled wafers comprising in combination, a wafer sheet supporting plate having spaced concavities, a die or stencil plate adapted to be superposed upon said supporting plate, and means for supplying filling through said die or stencil plate to the said concavities of wafer sheet upon the supporting plate.

3. Mechanism for forming filled wafers comprising in combination, means to receive a pair of matching wafer sheets, a die or stencil plate adapted to be superposed upon said means, means for supplying filling through said die or stencil plate to said wafer sheets, and means to superimpose one of said sheets upon the other.

4. Mechanism for forming filled wafers comprising in combination, a wafer supporting plate having a pair of members shaped to receive matching wafer sheets, a die or stencil plate adapted to be superimposed upon said plate, and means for supplying filling through said die or stencil plate to the wafer sheet upon said supporting plate.

5. Mechanism for forming filled wafers comprising, in combination, a wafer sheet supporting plate having spaced concavities, a die or stencil plate superimposed upon said plate and adapted thus to contact with the exposed surface of said wafer sheet, the openings in the die or stencil plate register-

ing with said concavities and means for supplying filling through the openings of said die or stencil plate to the concavities of said wafer sheet.

6. Mechanism for forming filled wafers comprising, in combination, a wafer sheet having spaced concavities, a die or stencil plate adapted to be superimposed upon said plate and adapted to contact with the exposed surface of the wafer sheet thereon, a hopper for filling material, and means relatively to traverse the hopper and the supporting and stencil plates.

7. Mechanism for forming filled wafers comprising, in combination, a wafer sheet supporting plate having two joined members adapted to be superimposed one upon the other, a die or stencil plate adapted to be superimposed flatwise upon said plate and adapted to contact with the wafer sheets thereon, said die or stencil plate being mounted for movement from active position, and hopper means for applying filling material through the openings of said stencil plate to the wafer sheets.

8. Mechanism for forming filled wafers comprising in combination, a wafer sheet supporting plate composed of a plurality of sections adapted to be brought into face to face relation, and a die or stencil plate adapted to be superimposed flatwise upon said supporting plate and having filling receiving openings.

9. Mechanism for forming filled wafers comprising in combination, a wafer sheet supporting plate, a die or stencil plate adapted to be applied to the supporting plate and having therein a plurality of spaced openings, the portions of the die or stencil plate about said openings being adapted to shield portions of the wafer sheet supporting plate, and means to supply filling through the said openings of the die or stencil plate to spaced areas of said supporting plate.

10. Mechanism for forming filled wafers comprising in combination, a wafer sheet supporting plate having a series of spaced concavities, and a die or stencil plate superimposed thereon for permitting the application to said concavities only of a predetermined measured quantity of filling slightly exceeding the capacity of said concavities, said die or stencil plate having a series of spaced openings adapted to register with said concavities, whereby said die or stencil plate shields a wafer sheet supporting plate except at the spaced concavities thereof.

11. Mechanism for forming filled wafers comprising in combination, a wafer supporting mold plate having spaced concavities, a die or stencil plate adapted to be superimposed flatwise thereagainst and adapted to contact with the exposed surface of the wafer sheet upon said plate, said stencil

plate being hinged, thereby to permit it to be swung away from said wafer sheet, and means for supplying filling through the die or stencil plate to the wafer sheet upon the 5 supporting mold plate.

12. Mechanism for forming filled wafers comprising in combination, a wafer sheet receiving mold plate composed of a plurality of relatively movable sections for effecting 10 superposition of wafer sheets supported thereon, and a die or stencil plate mounted to contact with the upper face of the sheet upon said mold plate.

13. Mechanism for forming filled wafers 15 comprising in combination, a wafer sheet receiving mold plate having a plurality of spaced concavities and a die or stencil plate pivoted in substantially the plane of the upper face of the mold plate and having 20 openings adapted to register with said concavities.

14. Mechanism for forming filled wafers comprising, in combination, a wafer sheet receiving, two member, mold plate said 25 members being relatively movable and a stencil plate mounted to contact with the upper surface of the sheet upon said mold plate.

15. Mechanism for forming filled wafers 30 comprising, in combination, a two-member, wafer sheet receiving mold plate, said members being relatively movable and a stencil plate pivoted in substantially the plane of the upper face of said mold plate.

35 16. Mechanism for forming filled wafers comprising in combination, a two member, wafer sheet receiving mold plate, said members being relatively movable and a stencil plate mounted to contact with the upper 40 surface of the sheet upon said mold plate, and a hopper movable to and fro along the upper face of the stencil plate.

17. Mechanism for forming filled wafers comprising, in combination, a two member, 45 wafer sheet receiving mold plate, said members being relatively movable and a stencil plate pivoted in substantially the plane of the upper face of said mold plates, and a hopper movable to and fro along the upper 50 face of the stencil plate.

18. Mechanism for forming filled wafers comprising, in combination, a two member, wafer sheet receiving mold plate, said members being relatively movable and a stencil 55 plate mounted to contact with the upper surface of the sheet upon said mold plate, a hopper and means to impart relative to and fro movement to said hopper and the stencil and mold plates.

60 19. Mechanism for forming filled wafers comprising, in combination, a two-member, wafer sheet receiving mold plate, said members being relatively movable and a stencil plate pivoted in substantially the plane of 65 the upper face of said mold plate, a hopper,

and means to impart relative to and fro movement to said hopper and the stencil and mold plates.

20. Mechanism for forming filled wafers comprising, in combination, a wafer sheet 70 supporting mold plate composed of two members hinged together, and a die or stencil plate pivoted to contact at the face of the sheet upon said mold plate.

21. Mechanism for forming filled wafers 75 comprising, in combination, a two member, wafer sheet receiving mold plate, said members being relatively movable and a stencil plate pivoted in substantially the plane of the upper face of said mold plate, a hopper, 80 and rack and pinion means to reciprocate the hopper along the face of the stencil plate.

22. Mechanism for forming filled wafers comprising, in combination, a wafer sheet 85 receiving mold plate composed of two members movable into superposition, and a hinged stencil or die plate mounted in substantially the plane of the upper face of the mold plate.

23. Mechanism for forming filled wafers comprising in combination, a two part, hinged, wafer sheet receiving mold plate and a stencil plate hinged at right angles 90 to the hinge of said mold plate.

24. Mechanism for forming filled wafers comprising in combination, a wafer supporting plate having a pair of members shaped to receive matching wafer sheets, said members being relatively movable so as to bring the wafer sheets thereon into superposition, a die or stencil plate adapted to be superimposed upon said wafer supporting plate, and having a plurality of openings through which filling material may be applied to at least one of said wafer sheets and whereby the remaining portion of said wafer sheet is shielded by the surrounding portions of said die or stencil plate, and means for supplying filling 100 through said die or stencil plate to the wafer sheet upon said supporting plate.

25. Mechanism for forming filled wafers comprising in combination, a wafer sheet supporting plate having two joined members adapted to be superimposed one upon the other, said plate having spaced concavities, a die or stencil plate adapted to be superimposed flatwise upon said wafer sheet supporting plate and adapted to contact with the wafer sheets thereon, said die or stencil plate being mounted for movement from active position, and hopper means for applying filling material through the openings of said stencil plate to the wafer sheets 110 120 at said concavities.

26. Mechanism for forming filled wafers comprising in combination, a wafer sheet supporting plate having two joined members adapted to be superimposed one upon the 125 130

other, a die or stencil plate pivoted in operative relation to said wafer sheet supporting plate and adapted to be superimposed flatwise thereon and to contact with the wafer 5 sheets thereon, and hopper means for applying filling material through the openings of said stencil plate to the wafer sheets.

27. Mechanism for forming filled wafers comprising in combination, a wafer sheet 10 supporting plate formed in sections hinged together, said sections having spaced concavities, and a die or stencil plate adapted to be superimposed flatwise upon said supporting plate and having filling receiving 15 openings adapted to register with said spaced concavities.

28. Mechanism for forming filled wafers comprising in combination, a wafer sheet supporting plate, and a die or stencil plate 20 adapted to be applied to the supporting plate and having therein a plurality of spaced openings, the portions of the die or stencil plate about said openings being adapted to shield portions of the wafer 25 sheet supporting plate.

29. Mechanism for forming filled wafers comprising in combination, a wafer sheet supporting plate, a die or stencil plate adapted to be applied to the supporting 30 plate and having therein a plurality of

spaced openings, the portions of the die or stencil plate about said openings being adapted to shield portions of the wafer sheet supporting plate, and means to supply filling by a wiping action through the 35 said openings of the die or stencil plate to spaced areas of said supporting plate.

30. Mechanism for forming filled wafers comprising in combination, two wafer sheet supporting plates, means to superpose one 40 of said plates with its supported wafer sheet upon the other, and two die or stencil plates adapted to be applied to the supporting plate prior to said superposition, and each having therein a plurality of spaced 45 openings, the portions of the die or stencil plates about said openings being adapted to shield portions of the wafer sheet supporting plates, and means to supply filling through said openings of the die or stencil 50 plates to spaced areas of said supporting plates.

In testimony whereof, I have signed my name to this specification, in the presence of two subscribing witnesses.

EDWARD E. LAWRENCE.
